Richard B. Oliver,
ATTORNEY

UNITED STATES PATENT OFFICE.

CHARLES W. ROBERTSON, OF PHILADELPHIA, PENNSYLVANIA.

CREEP JACK.

Application filed January 20, 1922. Serial No. 530,712.

To all whom it may concern:

Be it known that I, CHARLES W. ROBERTSON, a citizen of the United States, residing at Philadelphia, in the county of Philadelphia and State of Pennsylvania, have invented certain new and useful Improvements in Creep Jacks, of which the following is a specification.

This invention relates to a creep jack and more particularly to a novel and improved rolling stock device whereby a railroad car for instance, may be moved along the track by hand or motor power.

The primary object of the invention resides in the construction of a jack which may be positioned beneath and at one side of a disabled car in such manner that the car may be slightly raised from the truck and by applying manual or motor power the said car may be moved forward or backward to the desired position by the operator.

Another and very important object of the invention is the construction of a creep jack of the type above set forth which is applicable for use in connection with various types of railway cars and rolling stock in general, permitting the jack to be placed beneath a car coupler or other suitable position with respect to the frame and body of the car so that the same may be slightly raised, including a novel and improved gearing and operating mechanism for the jack which enables the same to move the car and also act as a brake when the car is being moved on an incline or grade.

I attain the above objects and others by the accompanying drawing, wherein,

Figure 1 is a side view partly in section. Figure 2 is an end view showing the application of a motor to the operating mechanism, and

Figure 3 is a view taken on the line 3—3 of Figure 1.

Referring now to the drawings, wherein like reference characters designate corresponding parts throughout the several views, 5 designates the frame or body of the jack, 6 the front and rear axles and 7 the flanged wheels which are adapted to ride on the tracks 8 as clearly disclosed by Figures 1 and 2 of the drawings. Rising cen-

trally of the frame 5 there is provided a column 9 of substantial diameter, the upper end of said column being threaded as shown 55 at 10 to receive the internally threaded, vertically movable, rotatable collar 11, the same being provided with apertures 12 radially disposed to permit of its rotation and vertical adjustment with respect to 60 the body of the car. The center rotatable member 11 is adapted to bear against the stationary member or body engaging member 13 which is provided with a vertical flange 14 whereby said stationary member 65 may be positioned with respect to the body of the car and retained by the threaded screw 15 in position when the rotatable member 11 is actuated in raising the car slightly from its seat. In other words, by 70 positioning the jack beneath the car body and transferring the weight from its wheels to the wheels 7 of the jack, the car may be moved backward and forward by the gearing and operating mechanism now to be described in detail.

A transversely extending shaft 16 operable in suitable bearings on the frame 5 is provided at one end with a spoke crank 17 whereby the said shaft may be rotated 80 and with a worm gear 18 at its opposite end the latter gear being in constant mesh with gear 19 rotatable on a short longitudinally extending stub shaft 20 which is rotatable in a bearing 21 on the outer side of the column 9 above referred to. The opposite end of the stub shaft 20 is also provided with a worm gear 22 engaging a spur gear 23 of a second horizontal shaft 24 parallel with the shaft 16 above referred to. The shaft 90 24 is also operable in bearings 25 on the frame 5 and carries at its outer end a sprocket wheel 26. A sprocket wheel 27 rotatable with the axle 6 is provided with the sprocket chain 28 chained over the first 95 mentioned sprocket 26 for communicating power to the said axle and consequently moving the jack as desired.

Referring to Figure 2 it will be observed that I have provided a motor designated 100 in its entirety by numeral 30 mounted on the bracket 31 of the frame so that power may be communicated to the shaft 16 independently of the spoke crank and thus

permit of the operation of the jack with greater speed. In the operation of the jack as above set forth it will be seen that when the same is positioned beneath a bumper, for instance, of a railway car and the stationary member 13 secured by the screw 15, by simply inserting a bar in any of the apertures 12 the collar 13 may be actuated so that the same will bear upwardly on the member 13 and raise the car from its truck 10 slightly. As the car is raised the weight thereof will be removed from its wheels and transferred to the wheels 7 of the creep jack so that when the operating mechanism 15 is actuated manually or by power the car may be moved either forwardly or rearwardly as desired. It will thus be seen that the shaft also acts in the nature of a braking mechanism due to the arrangement of 20 the gears so that on a grade the movement of the car can be checked and the operator may control the same at all times either by the motor or by spoke crank.

In the accompanying drawings, I have 25 illustrated my invention embodied in one form by way of example, and which construction has been found to answer to a satisfactory degree the results to be obtained. It would be manifest, however, 30 that other forms of embodiment may be adopted, and that the construction may be variously changed and modified by the skilled mechanic without departing from the limits of the invention. Further it will be 35 understood that the invention is not limited to any particular form of construction in the parts, except in so far as such limitations are specified in the subject matter being claimed.

Having thus described my invention what 40 I claim as new and desire to secure by United States Letters Patent is:

1. A creep jack of the class described comprising a wheel supported frame, a column rising from the frame and threaded at 45 its upper end, a vertically adjustable collar on the threaded portion of the column for raising a car body, and gearing for operating the wheel supported frame.

2. A creep jack of the class described 50 comprising a wheel supported frame, supporting axles for said frame, a column rising centrally from the frame and threaded at its upper end, a manually adjustable collar on the threaded portion of the column, a 55 stationary car body engaging member above the collar whereby the said body may be raised and gearing cooperating with one of the supporting axles for propelling the wheel supported frame.

3. A creep jack of the class described comprising a wheel supported frame, supporting axles for the frame, rotatable means mounted centrally of the frame for raising a car body, a pair of horizontal shafts 65 rotatable in bearings on said frame, a longitudinal stub shaft and meshed gears between the horizontal shafts, sprocket and chain gearing between one of the horizontal shafts and one of the supporting axles and means 70 for actuating said shafts and gearing to propel the jack.

In testimony whereof I affix my signature in presence of two witnesses.

CHARLES W. ROBERTSON. [U.S.]
